W. L. Childs, Inventor
By his Attorney Jesse R. Stone

UNITED STATES PATENT OFFICE.

WILLIAM L. CHILDS, OF HOUSTON, TEXAS, ASSIGNOR TO HUGHES TOOL COMPANY, OF HOUSTON, TEXAS, A CORPORATION OF TEXAS.

DRILL BIT.

1,406,931.

Specification of Letters Patent. Patented Feb. 14, 1922.

Application filed January 13, 1920. Serial No. 351,222.

To all whom it may concern:

Be it known that I, WILLIAM L. CHILDS, a citizen of the United States, residing at Houston, Harris County, Texas, have invented a certain new and useful Improvement 5 in Drill Bits, of which the following is a full, clear, and exact description, such as will enable others skilled in the art to which it appertains to make and use the same.

10 My invention relates to an improvement in drill bits, but has particular application to the type of bit ordinarily used in drilling in soft formation, such as clay, gumbo or similar material.

15 The object of my invention is to provide a means for preventing the sticking of the material to the drill and drill collar while the drilling operation is being performed.

20 Referring to the drawings forming a part of this specification and wherein like parts are designated by like numerals of reference in both the views, Fig. 1 is a side elevation of a fish tail bit with my improvement thereon; Fig. 2 is a central longitudinal section 25 of the device shown in Fig. 1 taken at right angles to the position shown in that figure.

30 In the drilling of wells and mines for oil, gas, sulfur, etc., the common type of bit used when operating in soft formation is the fish-tail bit, the common form of which is represented in the figures. The difficulty experienced while working in soft formation is that the flushing water, which is pumped 35 down through the drill stem, serving to carry away the cuttings from the bit, and raising them in suspension to the surface of the ground, does not act to carry away the cuttings with sufficient rapidity to prevent 40 their forming a ball about the bit, sticking to the blade and shank thereof, and so clogging the action of the bit that it ceases to function. It is the object of this improvement to supply a lubricant to the face of the cutting blade which will act to prevent the 45 sticking of the material thereto and thus maintain a clean surface at all times and prevent the balling up of the bit.

50 In Fig. 1 I have shown an ordinary type of fish-tail bit having a flattened blade 3 with a lower cutting edge thereon and an upper cylindrical threaded shank 4 for attachment to the drill collar, not shown. At the upper end of the shank 4 there is provided a threaded nipple 5 of reduced diameter.

ter, which is connected by means of a special coupling 6 to the lubricant container 7, said container being covered at the upper end by a cap 8 threaded thereon.

The coupling 6 is of special construction 60 having therein a valve 9 closing a central passage 11 leading from the lubricator 7 downward to a small chamber 12 within the nipple 5 of the bit. A squared end 10 upon the valve 9 is provided whereby the 65 valve may be turned to open or close the passage from the lubricator to the bit.

The lubricant is supplied from the chamber 12 in the upper end thereof to the blade 70 of the bit by means of a series of oil ducts which serve to conduct the oil and lubricant to different portions of the blade. There is a central channel 13 leading directly downward through the blade of the bit to a point centrally thereof from which there are two 75 branching ducts 13' which feed the oil to the opposite sides of the blade, as shown in Fig. 2. Lubricant is also fed to the upper end of the blade on each side thereof by two laterally inclined ducts 14 discharging 80 through openings 15 onto the face of the blade. Through these series of ducts lubricant may be fed upon the blade during the operation thereof so as to furnish a film of oil over practically the entire area of the 85 blade.

The lubricant is forced downwardly through the oil ducts 13 and 14 from the lubricator by means of a small piston 16 which is adapted to fit snugly within the 90 tubular lubricant container 7 and to rest upon the upper surface of the oil. The cap 8 is provided with a central opening 17 which allows the entrance thereto of flushing water from within the drill stem. This 95 water is under pressure, not only from the pumps but from the static head within the well. This pressure is exerted upon the piston 16 and acts to force it downwardly upon the lubricant so as to project this lubricant 100 through the ducts 13 and 14 to the blade. This type of lubricator is not new in the art but is used for a new purpose in this relation.

The flushing water within the drill stem is 105 also supplied to the upper surface of the blade through channels 18 which lead from the upper end of the shank 4 downwardly so as to discharge through openings 19 onto the upper faces of the blade of the bit. This 110

flushing water acts to carry away the disintegrated material.

The operation of this invention will now be obvious. The bit is attached to the drill collar and the drill stem in the usual manner, the bit having first been provided with the lubricator attachment just described. The length of the lubricant container 7 may be sufficient to hold a supply of lubricant to 10 operate for the desired length of time. The drill may be rotated and the flushing water be discharged during the operation downwardly through the ducts 18 upon the blade, and the pressure of the flushing water upon 15 the piston 16 will discharge the lubricant slowly through the ducts 13 and 14 onto the face of the blade. The lower cutting points of the blade will, because of their scraping action upon the material, maintain themselves clear of the disintegrated matter, and the discharge of the oil through the ducts onto the face of the blade will provide a film of oil which will prevent the adherence of the clay or gumbo to the upper part of the 20 blade. It has been found that the carrying away of the disintegrated material by the flushing water will also cause the oil from the ducts 13 and 14 to be carried upwardly along the drill collar and the lower end of 25 the drill stem, serving to cover them also with a film of oil, thus also preventing them from being covered with the viscous material being cut by the bit. A fish tail bit thus provided with a lubricating means such as 30 35 herein shown will work for long periods in

soft formation without the necessity of spudding or of withdrawing the bit from the well to clear the same of material. There will be a great saving in time usually consumed in clearing the bit periodically of the material adhering thereto. 40

Having thus described my invention, what I claim as new and desire to protect by Letters Patent is:

1. In an earth boring drill, the combination of a fish tail blade, a lubricant container thereon, means to conduct lubricant from said container to the face of said blade and means to conduct flushing water to the bottom of the hole being drilled in the manner 45 and for the purpose described.

2. In an earth boring drill, a fish tail blade having a shank thereon, a lubricant container attached to said shank, said shank having ducts leading from said lubricant 50 container to the opposite faces of said blade, and means to force the lubricant downwardly through said ducts.

3. In an earth boring drill, a shank, a blade thereon, said shank and blade having 55 a series of oil ducts discharging from said blade onto its working surface, a nipple on the upper end of said shank, a lubricant container attached thereto, and means to force lubricant from said container downwardly onto the face of the said blade. 60

In testimony whereof, I hereunto affix my signature this the 8th day of January A. D., 1920.

W. L. CHILDS
